PAGE 3

Fig. 3

*Fig. 4*FIG. 1 is a perspective view of a combined portable motion picture projector and carrying case therefor, taken from the front and one side, with the carrying case cover removed and the reel arms moved to an operative position, showing our new design.

FIG. 2 is a side perspective view of the side opposite to that shown in FIG. 1. The broken line illustration of the reels being for illustrative purposes;

FIG. 3 is a rear elevational view thereof; and

FIG. 4 is a perspective view thereof corresponding to FIG. 1 as it appears with the reel arms lowered and with the carrying case cover in place.

The dominant feature of the design resides in the portions shown in solid lines.

We claim:

The ornamental design for a combined portable motion picture projector and carrying case therefor, as shown and described.
